FIG. 1.

FIG. 2.

INVENTOR
GEORGE P. WASHBURN
BY *Hazard & Miller*
ATT'YS.

UNITED STATES PATENT OFFICE.

GEORGE P. WASHBURN, OF LOS ANGELES, CALIFORNIA, ASSIGNOR OF ONE-HALF TO
GEORGE H. WASHBURN, OF BREMERTON, WASHINGTON.

GAS AND AIR MIXER.

1,314,919.

Specification of Letters Patent.

Patented Sept. 2, 1919.

Application filed April 21, 1919. Serial No. 291,743.

To all whom it may concern:

Be it known that I, GEORGE P. WASHBURN, a citizen of the United States, residing at Los Angeles, in the county of Los Angeles 5 and State of California, have invented new and useful Improvements in Gas and Air Mixers, of which the following is a specification.

My invention relates to acetylene burners 10 and consists of the novel features herein shown, described and claimed.

Specifically my object is to make an improved valve mechanism for controlling acetylene and controlling an acetylene 15 burner.

Figure 1 is a fragmentary side elevation of an acetylene burner provided with a valve mechanism embodying the principles of my invention.

Fig. 2 is a horizontal sectional detail upon an enlarged scale and upon the line 2—2 of Fig. 1.

Referring to the drawing the acetylene tank 1 is provided with a permanent valve 25 construction 2 having an outlet nipple 3, the tank 1, the valve construction 2 and the outlet nipple 3 being of the usual construction.

The acetylene burner proper 4 is preferably constructed as shown, described and 30 claimed in my companion application for acetylene burners, filed Nov. 14, 1918, Serial Number 262,540, but the burner may be any of the usual constructions.

My present invention relates to the controlling valve mechanism 5 and the details 35 are as follows:

The main body 6 is formed integral with the union nipple 7, the burner feed pipe 40 nipple 8, the air intake nipple 9, the stuffing box nipple 10, and the stuffing box nipple 11. A union 12 connects the nipple 7 to the nipple 3. A needle valve bore 13 extends from the end of the stuffing box 10 to the needle valve seat 14. A port 15 extends from the 45 needle valve seat 14 and a port 16 extends from the bore 17 and the bore 17 extends from the end of the nipple 7, said ports 15 and 16 intersect at right angles. A needle valve 18 is screw-seated in the bore 13 and 50 a stuffing box 19 is formed around the needle valve 18 at the end of the nipple 10.

A hose fitting 20 is screwed into the nipple 8 and a burner feed hose 21 connects the hose fitting 20 to the burner 4. A hose fitting 22 55 is screwed into the nipple 9 and the air sup-

ply hose 23 is connected to the hose fitting 22 and to the source of the air supply or to an oxygen tank. A needle valve bore 24 is formed from the opposite side of the casting 6 from the nipple 11. A port 25 leads 60 from the nipple 8 to the bore 24 and a port 26 leads from the nipple 9 to the bore 24. A valve seat 27 is screw-seated in the bore 24 behind the port 26 and a plug 28 is screw-seated in the end of the bore 24 at the opposite side of the port 26 from the valve seat 27. A port 29 is formed cross-wise of the bore 24 behind the valve seat 27 to connect the bore 24 to the bore 13. The outer end of the hole made in producing the bore 29 70 is plugged by the screw 30. A needle valve 31 is screw-seated through the nipple 11 into the bore 24 against the valve seat 27 and a stuffing box 32 is formed upon the nipple 11 around the valve 31.

When the needle valve 31 is opened the air will pass through the hose 23, through the hose fitting 22, through the port 26, through the valve seat 27, through the bore 24, through the port 25, through the hose fitting 20 and through the hose 21 to the burner 4, and when the needle valve 18 is opened the acetylene will pass from the tank 1 through the valve construction 2, through the nipple 3, through the nipple 7, 80 through the port 16, through the port 15, pass the valve seat 14, through the port 9, through the bore 24, through the port 25, through the hose fitting 20 and through the hose 21 to the burner 4, and the mixture of 85 the air and acetylene may be accurately regulated by manipulating the needle valves 18 and 31.

The bore 24 is somewhat larger than the stem of the needle valve 31 all the way from 95 the contacting point of the valve to the screw threads so as to make a clear passage from the port 29 to the port 25 and this passage is of considerable length and provides a chamber in which the air and acetylene will mix. The pressure of the acetylene is against the point of the needle valve 18 and the air pressure is against the point of the needle valve 31, thereby tending to keep the points clean and to make accurate 100 regulation easy.

The specific arrangement of the needle valves makes it possible to get all of the valve mechanism close together and at the same time have the needle valve handles pro- 110

ject in opposite directions and easily accessible for manipulation.

Various changes may be made without departing from the spirit of my invention 5 as claimed.

I claim:

1. The combination with an acetylene burner and an acetylene tank having an outlet nipple of a valve mechanism for controlling the burner; said valve mechanism comprising a casting having a union nipple extending from one side, a burner feed pipe nipple extending from the opposite side of the casting from the union nipple, 10 an air intake nipple extending from the same side of the casting as the burner feed pipe nipple, a stuffing box nipple extending from the same side of the casting as the union and at right angles to the union nipple, and a second stuffing box nipple extending in the opposite direction from the first stuffing box nipple and adjacent the burner feed pipe nipple; there being a needle valve bore extending from the end of 15 the first stuffing box nipple, a needle valve seat at the bottom of the bore, a port extending from the needle valve seat and a second port extending from the union nipple and intersecting the first port; a needle 20 valve in the needle valve bore against the valve seat; a stuffing box mounted upon the nipple around the needle valve; a hose fitting screwed into the burner feed pipe nipple; a hose connecting the hose fitting to the burner; a second hose fitting screwed into the air intake nipple; there being a second 25 needle valve bore formed from the opposite side of the casting from the second stuffing 30 box nipple, a port leading from the burner feed pipe nipple to the bore, a port leading 35 from the air intake nipple to the second needle valve bore, a second needle valve seat screw-seated in the bore behind the air intake port, a plug screw-seated into the bore at the opposite side of the air intake 40 port from the valve seat, there being a port formed cross-wise to connect the second bore behind the valve seat to the first needle valve bore behind the first valve seat, a second 45 needle valve screw-seated through the second stuffing box nipple into the second needle valve bore; and a stuffing box formed around the second needle valve.

2. In a valve mechanism for controlling an acetylene burner, a casting, an acetylene 50 needle valve and an air needle valve oppositely arranged in the casting; there being a burner feed pipe nipple and an air intake nipple extending from one side of the casting and an attaching nipple extending from the other side of the casting, and there being ports leading from the attaching nipple past the point of the acetylene needle valve to the air needle valve behind its point and ports leading from the air intake nipple past the point of the air needle valve and ports leading from the point of the air needle valve to the burner feed pipe nipple, so that the acetylene passing the acetylene needle valve will be mixed with the air passing the air needle valve and the mixture discharged through the burner feed pipe nipple.

2. In a valve mechanism for controlling an acetylene burner, a casting, an acetylene 55 needle valve and an air needle valve oppositely arranged in the casting; there being a burner feed pipe nipple and an air intake nipple extending from one side of the casting and an attaching nipple extending from the other side of the casting, and there being ports leading from the attaching nipple past the point of the acetylene needle valve to the air needle valve behind its point and ports leading from the air intake nipple past the point of the air needle valve and ports leading from the point of the air needle valve to the burner feed pipe nipple, so that the acetylene passing the acetylene needle valve will be mixed with the air passing the air needle valve and the mixture discharged through the burner feed pipe nipple.

In testimony whereof I have signed my name to this specification.

GEORGE P. WASHBURN.
